MOP

Margaret L. Buell, Dallastown, Pa., assignor to
Grey Iron Casting Company, Mount Joy, Pa.,
a corporation of Pennsylvania

Application March 21, 1934, Serial No. 716,699

7 Claims. (Cl. 15—120)

This invention relates to mops and more particularly to a mop of the self-wringing type.

An object of this invention is to provide in a mop structure, means whereby the absorbent portion thereof may be wrung out by a series of wringing operations, that is, the absorbent portion initially twisted as tight as possible and then locked and subsequently released and twisted additionally to wring out the wiper to an exceedingly dry condition.

A further object of this invention is to provide in a mop structure of this kind, means whereby the wiper will be held in operative position.

The above and various other objects and advantages of this invention will in part be described and in part be understood from the following detailed description of the present preferred embodiment, the same being illustrated in the accompanying drawing wherein:

Figure 1 is a detail front elevation partly broken away of a mop constructed according to the embodiment of this invention.

Figure 2 is a detail side elevation of the device partly broken away.

Figure 3 is an enlarged sectional view taken on the line 3—3 of Figure 2.

Referring to the drawing wherein like numerals of reference designate corresponding parts throughout the views, the numeral 10 designates generally a handle of suitable length provided at its inner end with a cross member 13 so as to facilitate the twisting operation of the mop structure, as will be hereinafter described.

An elongated rod 11 is secured to the outer end of the handle 10 and is provided with a looped head 12. A mop swab W is looped through the head 12 and this swab comprises a moisture absorbing means in the form of a pad having a plurality of strands of absorbent material suitably secured together.

A tubular slide member 14 is slidably and rotatably disposed on the rod 11 and is provided at its forward side with opposed elongated slots 15 which receive a stop pin 16 carried by the rod 11 adjacent the forward end thereof. The sleeve or tubular member 14 is provided with opposed trunnions 17 which are internally threaded one with a right hand thread and the other with a left hand thread, and threaded tightening elements 18 are threaded in the thread bores of the trunnions 17 and each bolt 18 is provided with a head 19 adapted to receive an end 20 of an operating arm structure, generally designated as 21 which may be welded or otherwise secured to the head 19.

The trunnions 17 are engaged by eye members 22 carried by links 23, which are disposed in opposed relation to each other and engage through the swab W. These link members 23 are disposed with the free ends in overlapping relation, as shown in Figure 2 and are provided with upturned end portions 24 to prevent the swab W from slipping off from the free ends thereof.

The wringing handle 21 comprises a pair of substantially straight rods 25 connected together at their inner ends as by a loop 26 and provided at their forward ends with divergent arms 27 having their extremities secured to the heads 19 of the threaded members 18 as by welding or other securing means. These rods 25 converge in a forward direction sufficiently so that their forward ends and the rear convergent ends of the arms 27 are spaced apart a distance slightly less than the diameter of the rod 11, and the arms 27 are inclined to the longitudinal axis of the rods 25 so that when the handle portion 26 is pressed against the rod 11, the convergent ends of the arms 27 and the forward ends of the rods 25 will be disposed on the opposite side of the rod 11 from the handle 26. In this manner, the arms 27 and the forward ends of the rods 25 comprise a locking means to lock the operating arm structure 21 upon the rod 11. When in inoperative position, the looped portion or handle 26 engages against the forward end of the handle 10 and is held against rearward movement thereby.

In the use and operation of the mop structure herein disclosed, when it is desired to use the structure to wipe a wet surface, the operating arm structure 21 will be disposed with the loop portion 26 against the rod 11 and with the clamping arms 27 engaging the rod 11 in a manner to prevent lateral swinging movement of the operating arm 21. Preferably the sleeve 14 is disposed adjacent the forward end of the rod 11 with the pin 16 engaging in the slot 15 of the sleeve 14 so that the wringing structure will be held against turning movement on the rod 11. In this position, the mop may be used to clean the desired surface.

When it is desired to wring the wiper W, the wringing handle 26 is pulled laterally of the rod 11 and the handle 10 so as to release the arms 27 from the rod 11, and this movement will cause the threaded locking members 18 to be moved axially toward the rod 11 because of the screw action.

In practice, the handle 26 may be moved for a distance away from the rod 11 in which posi-

tion the slide 14 may be freely moved longitudinally of the rod 11. However, a further movement of the handle 26 will cause the locking members 18 to frictionally engage the periphery 5 of the rod 11 so as to resist turning of the rod 11 relative to the handle 26. The handle 10 may then be turned against the resistance of the holding members 18 and when the wiper W has been twisted to a considerable extent, the handle 26 10 can be moved laterally an additional distance so that the slide 14 will be locked against movement longitudinally and circumferentially. The cross bar 13 can then be re-grasped and the handle 26 moved in slightly so that the handle 10 15 may be turned an additional amount until the wiper W has been twisted about the rod 11 sufficiently to wring out substantially all of the water absorbed thereby.

What is claimed is:—

1. A wringer mop, comprising a handle rod 20 having means to secure a portion of a mop swab at its outer end, a sleeve slidably and rotatably mounted on said rod and having a threaded opening through its side wall, means to secure another portion of the mop swab on said sleeve, a rod clamping bolt threaded in said opening, and an operating arm longer than the width of the palm of a hand substantially perpendicular to and fixed to said bolt at its outer end in such relation that the bolt is moved out of clamping 25 engagement with the rod when the arm is swung toward said rod to permit wringing of said mop swab by relative rotation of the sleeve and rod and the bolt engages the rod to lock the sleeve thereon when the arm is swung outwardly and transverse to the rod.

2. A wringer mop, comprising a handle rod having means to secure a portion of a mop swab at its outer end, a sleeve slidably and rotatably mounted on said rod and having a threaded opening 40 through its side wall, means to secure another portion of the mop swab on said sleeve, a rod clamping bolt threaded in said opening, an operating arm longer than the width of the palm of a hand substantially perpendicular to and fixed to said bolt at its outer end in such relation that the bolt is moved out of clamping engagement with the rod when the arm is swung toward said rod to permit wringing of said mop swab by relative rotation of the sleeve in the rod 45 and that the bolt engages the rod to lock the sleeve thereon when the arm is swung outwardly and transverse to the rod, and clamping means carried by said operating arm and engageable with said rod when said arm is swung toward said rod, for holding said operating arm in a position to maintain said clamping bolt in released position.

3. A wringer mop, comprising a handle rod 60 having means to secure a portion of a mop swab at its outer end, a sleeve slidably and rotatably mounted on said rod and having a threaded opening through its side wall, means to secure another portion of the mop swab on said sleeve, a rod clamping bolt threaded in said opening, an operating arm longer than the width of the palm 65 of a hand substantially perpendicular to and fixed to said bolt at its outer end in such relation that the bolt is moved out of clamping engagement with the rod when the arm is swung toward said rod to permit wringing of said mop swab by relative rotation of the sleeve and rod and that the bolt engages the rod to lock the sleeve thereon when the arm is swung outwardly and transverse to the rod, and a resilient clamping means carried 70 to the rod, and a resilient clamping means carried 75

by the arm intermediate the ends thereof to engage the rod for holding said clamping bolt in inoperative position when said arm is swung to a position substantially parallel with said handle rod.

4. A wringer mop, comprising a handle rod 5 having means to secure a portion of a mop swab at its outer end, a sleeve slidably and rotatably mounted on said rod and having a pair of opposed threaded openings through its side wall, 10 means to secure another portion of the mop swab on said sleeve, a pair of rod clamping bolts threaded one in each of said openings and an operating arm longer than the width of the palm of a hand substantially perpendicular to and 15 fixed to each of said bolts at their outer ends in such relation that the bolts are moved out of clamping engagement with the rod when the arm is swung toward the rod to permit wringing of said mop swab by relative rotation of the sleeve and rod and that the bolts engage the rod to lock the sleeve thereon when the arm is swung outwardly and transverse to the rod.

5. A wringer mop, comprising a handle rod 25 having means to secure a portion of a mop swab at its outer end, a sleeve slidably and rotatably mounted on said rod and having a pair of opposed threaded openings through its side wall, means to secure another portion of the mop swab on said sleeve, a pair of rod clamping bolts 30 threaded one in each of said openings, an operating arm longer than the width of the palm of a hand substantially perpendicular to and fixed to each of said bolts at their outer ends in such relation that the bolts are moved out of clamping engagement with the rod when the arm is swung toward said rod to permit wringing of said mop swab by relative rotation of the sleeve and rod and that the bolts engage the rod to lock the sleeve thereon when the arm is swung outwardly and transverse to the rod, and a pair of rod clamping members carried by said arm intermediate the ends thereof and engageable with the rod when the arm is swung toward the rod for holding the arm in a position substantially parallel with the rod and maintaining said clamping bolts in released position.

6. A wringer mop, comprising a handle rod having means to secure a portion of a mop swab at its outer end, a sleeve slidably and rotatably mounted on said rod and having an opening through its side wall, means to secure another portion of the mop swab on said sleeve, an elongated rod clamping member extending through said opening and rotatably mounted and retained against accidental longitudinal displacement, and an operating arm longer than the width of the palm of the hand substantially perpendicular to and fixed to said clamping member at its outer end, cam means associated with said sleeve and said member to move a portion of the inner end of the member into clamping engagement with the rod by a thrust along the longitudinal axis of the elongated member upon swinging of the arm outwardly from and transverse to the rod and adapted to move said portion out of clamping engagement with the rod upon swinging of the arm toward the rod to permit wringing of the mop swab by relative rotation of the sleeve and rod.

7. A wringer mop, comprising a handle rod having means to secure a portion of a mop swab at its outer end, a sleeve slidably and rotatably mounted on said rod and having a pair of opposed openings through its side wall, means to 70

secure another portion of the mop swab on said sleeve, a pair of elongated rod clamping members extending through said openings one in each of said openings and rotatably mounted and retained against accidental longitudinal displacement, and an operating arm longer than the width of the palm of the hand substantially perpendicular to and fixed to each of said clamping members at its outer end, cam means associated with said sleeve and said members to

move a portion of the inner end of the members into clamping engagement with the rod by a thrust along the longitudinal axis of the elongated members upon swinging of the arm outwardly from and transverse to the rod and adapted to move said portion out of clamping engagement with the rod upon swinging of the arm toward the rod to permit wringing of the mop swab by relative rotation of the sleeve and rod.
